UNITED STATES PATENT OFFICE.

CHRISTIAN AALBORG, OF WILKINSBURG, PENNSYLVANIA, ASSIGNEE TO WESTINGHOUSE ELECTRIC AND MANUFACTURING COMPANY, A CORPORATION OF PENNSYLVANIA.

OIL-CUP.

1,189,221.

Specification of Letters Patent.

Patented July 4, 1916.

Application filed October 27, 1915. Serial No. 58,168.

To all whom it may concern:

Be it known that I, CHRISTIAN AALBORG, a citizen of the United States, and a resident of Wilkinsburg, in the county of Allegheny and State of Pennsylvania, have invented a new and useful Improvement in Oil-Cups, of which the following is a specification.

My invention relates to oil cups and particularly to closures for the same, and it has 10 for its object to provide an oil cup comprising a small number of simple and inexpensive parts that may be readily assembled.

In the accompanying drawings, Figure 1 is a view, partially in section and partially 15 in side elevation, of a dynamo-electric machine in which the shaft bearings are provided with oil cups constructed in accordance with my invention; Fig. 2 is an enlarged plan view of one of the oil cups shown in 20 Fig. 1, and Fig. 3 is a sectional view along the line III—III of Fig. 2 and including a portion of the bearing member shown in Fig. 1.

The oil cup comprises a tube 1 that is 25 slightly tapered toward one end and is expanded at the other end to form a cylindrical portion 2. The cylindrical portion 2 is provided with a laterally extending tongue 3 which is preferably formed by providing 30 parallel longitudinally extending slits in the walls of the cylindrical portion 2 and then bending out the wall between the slits. A U-shaped bracket member 4 is formed with its base 5 slightly concave to conform to the 35 outer surface of the cylindrical portion 2. An aperture 6 is provided in the base 5 of the bracket 4 and the bracket is secured to the tube 1 by inserting the tongue 3 within 40 the aperture 6 and then upsetting that portion of the tongue which projects beyond the base 5, as best shown in Fig. 3. A closure of cap 7 is formed from a suitable piece of sheet metal and is of substantially channel-shape 45 in cross section. One end of the cap 7 is rounded off to form a substantially semi-circular portion 8. The flanges 9 of the cap 7 are adapted to embrace the arms 4 of the bracket 4. The cap 7 is pivotally mounted on the bracket 4 by means of a rivet 10 which 50 extends through the adjacent flanges 9 and arms 4 of the cap and the bracket, respectively, the ends of the rivet 10 being upset in a well known manner. A coil spring 11 surrounds the rivet 10 and has its ends in engagement with the base of the bracket 4 and

the under surface of the cap 7, as best shown in Fig. 2. The end of the spring 11 in engagement with the bracket 4 being fixed, the other end of the spring tends to rotate the cap 7 in a clockwise direction and so maintain it in a closed position with respect to the tube 1. The oil cup, as a whole, is mounted in an opening 12 provided in the upper wall of a bearing member 13, as best shown in Fig. 1. The tapered portion of the tube 1 is adapted to wedge tightly into the opening 12 so that the opening is effectively closed except when the cap 7 is raised against the pressure of the spring 11 in order to inspect the bearing or to replenish the oil supply.

While I have shown my invention in a simple and preferred form, it is not so limited but is susceptible of various modifications within the scope of the appended 75 claims.

I claim as my invention:

1. An oil cup comprising a tube, a bracket secured to said tube, a cap pivotally mounted on said bracket, and means coacting with 80 said bracket for holding said cap in a closed position.

2. An oil cup comprising a tube, a bracket secured to said tube, a cap pivotally mounted on said bracket, and a resilient member interposed between said bracket and said cap for holding said cap in a closed position.

3. An oil cup comprising a tube, a cap for closing said tube and having a pivotal support carried by an extension of said tube, 90 and means carried by said pivotal support for maintaining said cap in a closed position.

4. An oil cup comprising a tube, a cap for closing said tube and having a pivotal support carried by an extension of said tube, and 95 a resilient member surrounding said pivotal support for maintaining said cap in a closed position.

5. An oil cup comprising a tube, a cap for closing said tube and having a pivotal support carried by an extension of said tube, and a coiled spring surrounding said pivotal support and having its ends engaging the 100 said extension and the said cap, respectively, for maintaining said cap in a closed position.

6. An oil cup comprising a tube, a cap for closing said tube and having a pivotal support carried by an extension of said tube, and a resilient member having its ends 105 engaging said extension and said cap, respec-

tively, for maintaining said cap in a closed position.

7. An oil cup comprising a tube having a projecting tongue portion, a bracket having an aperture adapted to be engaged by said tongue portion, and a cap pivotally mounted on said bracket for closing the said tube.

8. An oil cup comprising a tube, a U-shaped bracket secured thereto, a cap for

closing said tube and having a pivotal support carried by the arms of said bracket, and a resilient member carried by said pivotal support between the arms of said bracket for maintaining said cap in a closed position.

In testimony whereof, I have hereunto subscribed my name this 23rd day of Oct. 1915.

CHRISTIAN AALBORG.
